MINING MACHINE HAVING AUXILIARY CUTTERS DRIVEN FROM REAR OF DRUM SUPPORT

James Kilbourne, Bexley, Ohio, assignor to Jeffrey Galion Manufacturing Company, a corporation of Ohio
Filed Aug. 17, 1964, Ser. No. 390,040
12 Claims. (Cl. 299—76)

The instant invention relates to mining apparatus, and to the mechanism by which such mining apparatus is driven.

It is an object of the instant invention to provide an improved mining apparatus which is advanced into a mine face to remove material therefrom, and in which the cutting and breaking means is operable about an axis that is transversely disposed with respect to the direction of advance of the mining apparatus. The drive means for the cutting and breaking means is connected to the latter on the transverse axis at a position intermediate the ends of the same. An auxiliary cutting and breaking means is provided, and is operative in the area of the driving connection to the cutting and breaking means, to span this area and to provide cutting and breaking means across the full width of the mining apparatus.

Other objects of the invention will appear hereinafter, the novel features and combinations being set forth in the appended claims.

In the drawings:

FIG. 1 is a side elevational view of a mining machine incorporating the mining apparatus of this invention;

FIG. 2 is a plan view of the mining machine illustrated in FIG. 1;

FIG. 3 is a plan view, in section, of the mining apparatus of this invention, taken on the line 3—3 in FIG. 1;

FIG. 4 is a sectional view of the mining apparatus, taken on the line 4—4 in FIG. 3; and

FIG. 5 is a plan view of the auxiliary cutting and breaking means.

Referring to the drawings, there is illustrated in FIGS. 1 and 2 a mining machine 10 which incorporates the mining apparatus 11 of this invention. The mining machine 10 may be of the continuous type in which the mining apparatus 11 is disposed at the forward end thereof to be advanced into a mine face for cutting and breaking material out of such face. The mining machine 10 is supported on endless traction treads 12, 12, which are disposed one at each side of the machine and are suitably driven for propelling the mining machine 10.

A gathering means 13 is also disposed at the forward end of the mining machine 10. The gathering means 13 comprises an apron or deck 14 which slopes downwardly to the mine floor. Two gathering arms 15, 15 are mounted on the apron or deck 14, one at each side thereof, and operate with a sweeping motion to gather the mined material from the mine floor onto the apron 14 and to crowd the same into the chain and flight conveyor 16 which extends from the forward end of the mining machine 10 to the rear end thereof, at which there is a discharge boom 17 from which the material is discharged.

The gathering means 13 may be adjusted upwardly and downwardly to follow an uneven mine floor and thereby to maintain the leading edge of the apron or deck 14 on the mine floor for maximum effectiveness in loading the mined material into the conveyor 16. The discharge boom 17 is adjustable upwardly and downwardly and from side to side for directing the discharge of mined material from the mining machine 10.

The mining machine 10 has a boom 18 comprising side arms 19, 19 which are disposed in laterally spaced positions, approximately in alignment with the opposite sides

2

of the conveyor 16. The rear end of each side arm 19 is connected to the main frame 23 of the mining machine 10 by pivot support means 20, on which the boom 18 may be raised and lowered, and which additionally provide support for the load of the mining apparatus 11. A transverse reinforcing member 21 extends between the side arms 19, 19 and is secured thereto to provide the boom 18 with the requisite rigidity. Two cylinder and piston devices 22, 22 are disposed one at each side of the mining machine 10. These are secured to the mining machine main frame 23 and extend upwardly and forwardly therefrom to the boom 18, and are secured to the latter on suitable bifurcated brackets 24, 24, one at each side of the boom 18. The cylinder and piston devices 22, 22 are extensible and retractable to raise and lower the boom 18 and the mining apparatus 11.

Referring now to FIGS. 3 and 4, there is illustrated therein the mining apparatus 11 and the forward end of the boom 18 on which it is mounted. This structure is symmetrical about the longitudinal center line of the mining machine 10, and accordingly, FIG. 3 only illustrates the structure at one side of the mining machine 10, it being understood that the structure at the other side thereof is identical, except that it is oppositely arranged. Accordingly, the description will proceed in the singular with respect to the structure illustrated in FIG. 3, with the understanding that the description applies equally to the like structure at the other side of the longitudinal center line of the mining machine 10.

The mining apparatus 11 is secured to the boom 18 by engagement of rearwardly extending arms of a drive housing and main support 25 with the side arms 19, 19 of the boom 18, and is secured thereto by a plurality of bolts 26 or the like.

The mining apparatus 11 is driven from the motors 27, 27, which are disposed one at each side of the mining machine 10. The drive from the motors 27, 27 is delivered to transmissions 28, 28, and thence to universal shafts 29, 29. Each universal shaft 29 is connected to a drive shaft 30, which is rotatably mounted in the drive housing and main support 25, as seen in FIG. 3.

The end of the drive shaft 30 is formed with a bevel pinion 31 which engages a bevel gear 32 to drive the latter. The bevel gear 32 is rotatably mounted in the main support 25. The bevel gear 32 is secured to a hollow shaft 33, which extends laterally outwardly from the bevel gear 32 and is rotatably supported in the main support 25. The hollow shaft 33 is connected to a clutch 34, which is rotatably supported in the lateral housing extension 35 of the main support 25. The clutch 34 connects the shaft 33 to a shaft 36 which extends laterally inwardly from the clutch 34. The shaft 36 extends through the hollow shaft 33 and beyond the bevel gear 32, and is connected to a pinion 37 that is rotatably supported in the main support 25.

The main support 25 has a forward housing extension and support member 38. A reach gear 39 engages the pinion 37. The reach gear 39 is rotatably mounted in the forward housing extension 38 on a shaft 40. The reach gear 39 in turn engages a driven gear 41 to drive the latter. The driven gear 41 is fixedly secured to a rotatable shaft 42 that has its axis disposed transversely with respect to the longitudinal center line of the mining machine 10. The shaft 42 is supported by the forward housing extension and support member 38 and is rotatable with respect to the latter on a bearing 43, the member 38 being a fixed support for the transverse rotatable shaft 42. The driven gear 41 connects the drive means to the shaft 42.

The rotatable shaft 42 supports the cutting and breaking means of the mining apparatus 11. A split collar 45

is fixedly secured to the shaft 42 at the longitudinal center line of the mining machine 10. A circular flange member 46 has a hub 47 by which it is fixedly secured to the shaft 42. The circular flange member 46 is placed adjacent to one side of the support member 38. A circular frame 48 is secured to the circular flange member 46 by a plurality of bolts 49 or the like. The frame 48 is formed with a plurality of bit holders 50, in each of which there is secured a bit 51. The bits 51 are disposed in an imaginary cylindrical surface, and the transverse disposition thereof spans the distance between the circular flange member 46 and the longitudinal center line of the mining machine 10. The bit holders 50 and their bits 51 are an intermediate cutting and breaking means which is operative between the two forward housing extensions and support members 38, 38, as seen in FIG. 2.

At the outer side of the support member 38 there is a circular flange member 55 which is disposed closely adjacent to the support member 38. The circular flange member 55 has a laterally extending web 56 by which it is connected to a hub 57. The hub 57 is fixedly secured to the shaft 42, whereby the circular flange member 55 is rotatable with the shaft 42. A sleeve 58 is also fixedly secured to the shaft 42 to be rotatable therewith and is interposed between the bearing 43 and the hub 57. The sleeve 58 abuts the bearing 43, and the hub 57 abuts the sleeve 58. The several elements are maintained in assembly on the shaft 42 by a lock nut 59 which is threaded on the shaft 42 against the hub 57.

A cylindrical shell 60 is supported on the laterally extending web 56 of the circular flange member 55. At the inner end of the cylindrical shell 60 there is a radial flange 61 which abuts the circular flange member 55 and is secured thereto by a plurality of bolts 62 or the like. The cylindrical shell 60 extends outwardly from the circular flange member 55 along the shaft 42 and supports a portion of the outer cutting and breaking means of the mining apparatus 11. Such cutting and breaking means comprises two spiral flights 63, 64 which are secured to the cylindrical shell 60 to provide a double pitch spiral conveying or feeding means, which is operative to feed the mined material in towards the longitudinal center line of the mining machine 10 to facilitate the gathering and the loading of the mined material into the conveyor 16. A plurality of bit holders 65 are secured to the peripheral edges of the spiral flights 63, 64 at spaced positions, and a bit 66 is secured in each bit holder 65. The bits 66 are also disposed in an imaginary cylindrical surface, which is coincident with the imaginary cylindrical surface in which the bits 51 are disposed.

At the outer end of the cylindrical shell 60 there are a plurality of bit holders 67 and bits 68, which extend somewhat beyond the end of the cylindrical shell 60. These bit holders 67 and bits 68 are disposed in groups at spaced circumferential positions, of which there may be four groups. The bits 68 are disposed in the same imaginary cylindrical surface as the bits 51, 66.

At the outer end of the shaft 42 there is a sleeve 70 that is slidably mounted on the shaft 42, and is rotatably fixed with respect to the latter. The sleeve 70 may have a splined or keyed connection to the end of the shaft 42 for sliding movement relatively to the latter. An end cutting and breaking means has a disc-like element 71 formed with a hub 72 which is received on the end of the sleeve 70. An end cap 73 is secured to the end of the sleeve 70 by a plurality of bolts 74 or the like, and engages the end disc element 71 to fixedly secure it on the sleeve 70. A plurality of bit holders 75 are secured to the end disc element 71 on the periphery thereof, and each bit holder 75 has a bit 76 secured therein and extending radially outwardly. The bit holders 75 are disposed in groups, of which there may be four in number, and these are disposed at equally spaced positions around the periphery of the end disc element 71. The bit holders 75 and the bits 76 in each group are disposed at laterally

spaced positions so as to have a cutting and breaking effectiveness along a transverse distance. The several groups of bit holders 75 and bits 76 are alternated with the circumferential disposition of the several groups of bit holders 67 and bits 68.

The sleeve 70 is illustrated in FIG. 3 in its outermost position on the shaft 42. The sleeve 70 and the end disc element 71 may be withdrawn with respect to the cylindrical shell 60 to contract the rotary cutting and breaking means, whereby the width thereof along the transverse axis is reduced. Movement of the sleeve 70 along the shaft 42 may be effected by a plurality of cylinder and piston devices 77, which are disposed within the cylindrical shell 60 and are secured to the web 56 of the circular flange member 55, and to the sleeve 70. Retraction of the end disc element 71 places it adjacent to the end of the cylindrical shell 60, as seen in phantom lines in FIG. 3. The several groups of bit holders 75 and their bits 76 overlap the outer end of the cylindrical shell 60 and fit between the groups of bit holders 67 and bits 68 that are secured thereto. The cylinder and piston devices 77 may be hydraulically operated, and hydraulic connections, for applying hydraulic fluid under pressure to the cylinder and piston devices 77, may be effected through the support member 38 and the sleeve 58, with these elements forming a rotary hydraulic joint, and direct hydraulic connections may be made from the sleeve 58 to the cylinder and piston devices 77.

The cutting and breaking means which has been described thus far has its bits 51, 66, 76 disposed in a common imaginary cylindrical surface, with each bit traveling in a circular path upon rotation of the shaft 42. Such rotary cutting and breaking means is the main or prime cutting and breaking means of the mining apparatus 11. The portion thereof disposed between the support members 38, 38 is the intermediate portion of the main cutting and breaking means, and the portion thereof which is disposed laterally outwardly of the support member 38 is the outer portion of the main cutting and breaking means, there being two such outer portions, as seen in FIG. 2.

By reason of the support member 38, on which the shaft 42 and the rotary cutting and breaking means is supported, and in which the drive connection is effected to the shaft 42 on its transverse axis, there is a gap between the intermediate cutting and breaking means and each outer cutting and breaking means, in which the main cutting and breaking means is not operative. Such gap is filled by an auxiliary or secondary cutting and breaking means comprising an endless, flexible chain type of cutting and breaking means 80, which is adapted to operate on a support member 38, and is of such lateral width as to fill the gap between the intermediate cutting and breaking means and an outer cutting and breaking means.

The endless chain cutting and breaking means comprises a plurality of block links 81 which have a cross-like form, as best seen in FIG. 5. A pair of side bars 82, 82 are disposed between each pair of block links 81, 81 and are laterally spaced to receive the ends of the blocks links 81, 81 therebetween. A transverse pin 83 extends through each end of a block link 81 and the adjacent ends of the side bars 82, 82. The pin 83 may be fixedly secured to the side bars 82, 82 by a roll pin 84 or like means. The pin 83 is freely pivotal in an end of a block link 81, thereby forming, in each case, an articulated connection between a block link 81 and the side bars 82, 82.

The endless chain cutting and breaking means 80 has a plurality of cutting and breaking bits 85, which are secured in the block links 81 and the side bars 82. In block link 81a the bit 85 is secured at one side of the longitudinal center line, and in block link 81b the bit 85 is secured at the opposite side of the longitudinal center line. Block link 81c is disposed intermediate block links

31a, 81b, and it has a bit **85** secured thereto on the longitudinal center line.

A side bar **82a** is connected to block link **81a** and has a bit **85** secured thereto. A side bar **82b** is secured to the block link **81b**, and it also has a bit **85** secured thereto. Thus, there are five cutting and breaking bits **85** secured to the block links **81a, 81b, 81c**, and to the side bars **82a, 82b**, with these five bits **85** being disposed at five laterally spaced positions to provide cutting bits **85** across the full width of the endless chain cutting and breaking means **80**. This pattern of disposition of bits **85** repeats itself for the full length of the endless chain cutting and breaking means **80**. The cutting and breaking bits **85**, as thus disposed in laterally spaced disposition across the endless chain cutting and breaking means **80** effectively fill the gap over the forward housing extension and support member **38**, and between the intermediate portion and the outer portion of the cutting and breaking means.

The forward housing extension and support member **38** includes an arcuate guiding and supporting surface **86**, as best seen in FIGS. 3 and 4. The arcuate guiding and supporting surface is formed as a portion of a cylinder, having its axis coincident with the axis of the transverse shaft **42**. At each side of the guiding and supporting surface **86** there is a radially extending flange **87** to form with the guiding and supporting surface **86** an arcuate track, within which the endless chain cutting and breaking means **80** is operated. The links **81** and the side bars **82** of the endless chain cutting and breaking means **80** are seated on the guiding and supporting surface **86** and bear against the latter. With the cutting and breaking means **80** disposed on the surface **86**, the bits **85** are disposed in the same imaginary cylindrical surface as the bits **51, 66, 76**, for uniform cutting and breaking action on the material of the mine face.

The main support **25** is formed with a cavity **90** behind the support members **38, 38**. Each endless chain cutting and breaking means **80, 80** has a path that extends around a support member **38**, with a portion of a cutting and breaking means **80** being disposed on the arcuate guiding and supporting surface **86**, and through the cavity **90**, as seen in FIGS. 3 and 4. Within the cavity **90** there are two bifurcated supports **91, 91** which are laterally spaced from each other and extend rearwardly behind each support member **38**. A bearing block **92** is slidably supported in the bifurcated supports **91, 91**. A screw **93** is threadedly engaged with the bearing block **92** and abuts the main support **25**. The position of the bearing block **92** on the supports **91, 91** may be adjusted by rotation of the screw **93**. A shaft **94** is rotatably supported in the bearing block **92**. The bearing block **92** is bifurcated, whereby a portion of shaft **94** is exposed in the bearing block **92** for mounting a sprocket wheel **95** on the shaft **94** within the bearing block **92**. The teeth of the sprocket wheel **95** engage the endless chain cutting and breaking means **80**, with the teeth being received between the successive block links **81** thereof. The endless chain cutting and breaking means **80** is driven by the sprocket wheel **95**. The rotation of the sprocket wheel **95** is in a clockwise direction, as viewed in FIG. 4, whereby the chain cutting and breaking means **80** is pulled down and over the guiding and supporting surface **86** to maintain it in bearing engagement therewith during the cutting and breaking operation.

The shaft **94** is formed with a shaft extension **96**, to which there is secured a driven sprocket wheel **97**. The pinion **37** is likewise formed with a shaft extension **98**, to which there is secured a driving sprocket wheel **99**. The sprocket wheels **97, 99** are aligned with each other, and a drive chain **100** is engaged with the teeth of the sprocket wheels **97, 99** to provide a driving connection. Thus, there is formed a drive connection from the driving means of the main rotary cutting and breaking means to the auxiliary cutting and breaking means, for driving the latter. The sprocket wheel **95** is disposed at the rear end

of the support member **38**, and in addition to driving the endless chain cutting and breaking means **80**, such sprocket wheel **95** also provides guiding and supporting means for the endless chain cutting and breaking means **80** at the rear end of its path of movement.

In the operation of the mining machine **10** the boom **18** is raised to dispose the mining apparatus **11** at the level of the top of the mine face. The mining machine **10** is then propelled forwardly to advance the cutting and breaking means of the mining apparatus **11** into the mine face. During such advance, the cutting and breaking means is operative about its transverse axis, whereby the cutting bits thereof cut and break the material of the mine face. Such mined material is fed inwardly towards the longitudinal center line of the mining machine and rearwardly by the spiral flights **63, 64**, and the material is discharged out of the mine face onto the mine floor, to be gathered by the gathering means **13** and loaded into the conveyor **16**.

When the cutting and breaking means of the mining apparatus **11** has been advanced the desired distance into the mine face, the forward movement of the mining machine **10** is stopped, and thereafter, the boom **18** is moved downwardly, whereby the mining apparatus operates to further remove material from the mine face down to the bottom thereof at the mine floor.

The end cutting and breaking means, comprising the bit holders **75** and their bits **76** are normally placed in fully extended position so that the cutting and breaking means of the mining apparatus **11** forms an opening in the mine seam that is wider than the maximum width of the mining machine **10** behind the mining apparatus **11**. This permits the mining machine **10** to be propelled forwardly without interference with the rib at either side thereof. The end cutting and breaking means may be retracted when the mining machine **10** is trammed, so that this cutting and breaking means does not contact the rib at either side of the mining machine **10**.

The mining apparatus of this invention provides a highly effective cutting and breaking means for removing material from a mine face, in which cutting and breaking bits are disposed at positions across the full width of the mining apparatus. The drive means for the main cutting and breaking means is connected to the latter on its transverse axis to provide a highly effective power transmission for driving the main cutting and breaking means. The support members for the main cutting and breaking means also form housings for the drive connections to the main cutting and breaking means. The auxiliary cutting and breaking means is driven by drive connections from the driving means of the main cutting and breaking means. By the construction of this invention, the main cutting and breaking means and the auxiliary cutting and breaking means are both driven in such manner as to satisfy the power requirements for achieving a mining operation with a full width mining apparatus.

Obviously those skilled in the art may make various changes in the details and arrangement of parts without departing from the spirit and scope of the invention as defined by the claims hereto appended, and applicant therefore wishes not to be restricted to the precise construction herein disclosed.

Having thus described and shown an embodiment of the invention, what it is desired to secure by Letters Patent of the United States is:

1. Mining apparatus including a main cutting and breaking means adapted to be advanced into the material of a mine face to remove said material therefrom, said main cutting and breaking means being disposed on a transverse axis relatively to the direction of advance thereof into said material, means supporting said main cutting and breaking means for movement about said transverse axis, means for driving said main cutting and breaking means, means connecting said driving means to said main cutting and breaking means, portions of said

main cutting and breaking means being spaced from each other along said transverse axis, said connecting means being disposed between said spaced portions of said main cutting and breaking means, auxiliary cutting and breaking means disposed between said spaced portions of said main cutting and breaking means, driving connection of said driving means to said auxiliary cutting and breaking means, guiding and supporting means for said auxiliary cutting and breaking means and disposed between said spaced portions of said main cutting and breaking means, said driving connection including a driving element at the rear of said guiding and supporting means and in engagement with said auxiliary cutting and breaking means, and said auxiliary cutting and breaking means being driven by said driving element over said guiding and supporting means and about said transverse axis.

2. Mining apparatus including a rotary cutting and breaking means adapted to be advanced into the material of a mine face to remove said material therefrom, said rotary cutting and breaking means being disposed on a transverse axis relatively to the direction of advance thereof into said material, a housing for supporting said rotary cutting and breaking means for rotation around said transverse axis, means for driving said rotary cutting and breaking means, driving connection of said driving means to said rotary cutting and breaking means, said gear means being disposed within said housing, portions of said rotary cutting and breaking means being spaced from each other along said transverse axis, said gear means and said housing being disposed between said spaced portions of said rotary cutting and breaking means, auxiliary cutting and breaking means disposed between said spaced portions of said rotary cutting and breaking means, a portion of said housing forming a supporting and guiding means for said auxiliary cutting and breaking means, driving connection of said driving means to said auxiliary cutting and breaking means, said auxiliary cutting and breaking means being driven by said driving connection over said supporting and guiding portion of said housing and about said transverse axis, said auxiliary cutting and breaking means including an endless flexible cutting and breaking means that extends around said housing, and said driving connection including a driving element disposed beyond said housing and engaged with said endless flexible cutting and breaking means to drive the latter and to support and guide said endless flexible cutting and breaking means at the rear portion of its path of movement beyond said housing.

3. Mining apparatus including a rotary cutting and breaking means adapted to be advanced into the material of a mine face to remove said material therefrom, said rotary cutting and breaking means being disposed on a transverse axis relatively to the direction of advance thereof into said material, means supporting said rotary cutting and breaking means for rotation around said transverse axis, means for driving said rotary cutting and breaking means, connecting said driving means to said rotary cutting and breaking means, portions of said rotary cutting and breaking means being spaced from each other along said transverse axis, said connecting means being disposed between said spaced portions of said rotary cutting and breaking means, endless chain cutting and breaking means disposed between said spaced portions of said rotary cutting and breaking means, driving connection of said driving means to said endless chain cutting and breaking means, guiding and supporting means for said endless chain cutting and breaking means and disposed between said spaced portions of said rotary cutting and breaking means, said driving connection including a driving element at the rear of said guiding and supporting means and in engagement with said endless chain cutting and breaking means, and said endless chain cutting and breaking means being driven by said driving

element over said guiding and supporting means and around said transverse axis in a portion of its path.

4. Mining apparatus as recited in claim 3 in which said supporting means comprises a fixed member, said rotary cutting and breaking means includes a shaft disposed on said transverse axis, and means rotatably mounting said shaft on said fixed member.

5. Mining apparatus as recited in claim 4 in which said fixed member comprises a housing, said means connecting said driving means to said rotary cutting and breaking means being disposed within said housing, and said guiding and supporting means for said endless chain cutting and breaking means being formed on said housing.

6. Mining apparatus including a rotary cutting and breaking means adapted to be advanced into the material of a mine face to remove said material therefrom, said rotary cutting and breaking means being disposed on a transverse axis relatively to the direction of advance thereof into said material, means supporting said rotary cutting and breaking means for rotation around said transverse axis, means for driving said rotary cutting and breaking means, means connecting said driving means to said rotary cutting and breaking means, portions of said rotary cutting and breaking means being spaced from each other along said transverse axis, said connecting means being disposed between said spaced portions of said rotary cutting and breaking means, endless chain cutting and breaking means disposed between said spaced portions of said rotary cutting and breaking means, driving connection of said driving means to said endless chain cutting and breaking means, guiding and supporting means for said endless chain cutting and breaking means and disposed in a circular arc around said transverse axis and between said spaced portions of said rotary cutting and breaking means, said driving connection including a driving element at the rear of said guiding and supporting means and in engagement with said endless chain cutting and breaking means, and said endless chain cutting and breaking means being driven by said driving element with a portion of the path thereof extending around said transverse axis in said circular arc.

7. Mining apparatus as recited in claim 6 in which said endless chain cutting and breaking means comprises a plurality of links and laterally extending pins connecting said links one to another for articulation thereof, and said endless chain and said driving element including interengaging portions thereof by which the driving element drives the endless chain cutting and breaking means.

8. Mining apparatus as recited in claim 7 in which said driving element is a sprocket formed with circumferentially disposed teeth for engaging said endless chain cutting and breaking means and to support and guide the latter at one end of its path.

9. Mining apparatus including a rotary cutting and breaking means adapted to be advanced into the material of a mine face to remove said material therefrom, said rotary cutting and breaking means being disposed on a transverse axis relatively to the direction of advance thereof into said material, laterally spaced support members for said rotary cutting and breaking means, an intermediate portion of said rotary cutting and breaking means being disposed between said support members, first and second outer portions of said rotary cutting and breaking means one of which is disposed outwardly of one support member and the other of which is disposed outwardly of another of said support members for rotation thereof around said transverse axis, means for driving said rotary cutting and breaking means, means connecting said driving means to said rotary cutting and breaking means, said connecting means being disposed between said intermediate portion of said rotary cutting and breaking means and each of said first and second outer portions of said rotary cutting and breaking means,

auxiliary cutting and breaking means disposed between said intermediate portion of said rotary cutting and breaking means and each of said first and second outer portions of said rotary cutting and breaking means, driving connection of said driving means to said auxiliary cutting and breaking means, guiding and supporting means for said auxiliary cutting and breaking means and disposed between said intermediate portion of said rotary cutting and breaking means and each of said first and second outer portions of said rotary cutting and breaking means, said auxiliary cutting and breaking means being driven by said driving connection over said guiding and supporting means and about said transverse axis, said guiding and supporting means comprising a portion of said support members extending around said transverse axis, and said driving connection comprises driving elements at the rear of said support members disposed in driving engagement with said auxiliary cutting and breaking means.

10. Mining apparatus as recited in claim 9 in which said first and second outer portions of said rotary cutting and breaking means each includes an extensible and retractable cutting and breaking element, and means for extending and retracting said cutting and breaking element to lengthen and shorten said rotary cutting and breaking means, respectively.

11. Mining apparatus as recited in claim 9 in which said auxiliary cutting and breaking means comprises endless articulated chains, said driving elements comprise driving wheels, said endless articulated chains and said driving wheels including interengaging elements by which the driving wheels drive the endless articulated chains.

12. Mining apparatus including a rotary cutting and breaking means adapted to be advanced into the material of a mine face to remove said material therefrom, said rotary cutting and breaking means being disposed on a transverse axis relatively to the direction of advance thereof into said material, first and second laterally spaced support members for said rotary cutting and breaking means each composing a housing, an interme-

diate portion of said rotary cutting and breaking means being disposed between said first and second support members, first and second outer portions of said rotary cutting and breaking means disposed outwardly of said first and second support members, respectively, for rotation of the rotary cutting and breaking means around said transverse axis, means for driving said rotary cutting and breaking means, first and second means connecting said driving means to said rotary cutting and breaking means and disposed in the housings of said first and second support members, respectively, first and second auxiliary cutting and breaking means disposed between said intermediate portion of said rotary cutting and breaking means and said first and second outer portions of said rotary cutting and breaking means, respectively, first and second driving connections of said driving means to said first and second auxiliary cutting and breaking means, said first and second support members each being formed with guiding and supporting surfaces for said auxiliary cutting and breaking means and each disposed in an arc about said transverse axis, said first and second auxiliary cutting and breaking means being driven by said first and second driving connections over said guiding and supporting surfaces and about said transverse axis, and said first and second driving connections each including a driving element at the rear of said first and second support members, respectively, and said driving elements engaging said auxiliary cutting and breaking means and supporting and guiding the latter at one end of the path of movement thereof.
